UNITED STATES PATENT OFFICE.

MORGAN J. LEWIS, OF MASSILLON, OHIO, ASSIGNOR TO E. F. DUQUETTE, OF HARTVILLE, OHIO.

KEY-LOCKING ELECTRIC SWITCH.

Application filed January 26, 1927. Serial No. 163,670.

The invention relates to electric switches particularly adapted for controlling electrically operated door opening and closing devices such as set forth in my prior application for patent, Serial No. 105,115, wherein it may be desirable to have a control switch conveniently located outside the garage door, so that the driver of an automobile may direct his automobile toward the garage, and may operate the control switch preferably without getting out of the automobile.

For such an exteriorly located control switch, it is desirable to have a key locking device which will prevent anyone but the possessor of the key from operating the switch to control the door opening and closing mechanism.

Accordingly the objects of the present improvements are to provide a simple and economical key locking electric switch adapted for use in exterior locations, and also to provide a construction and arrangement therefor which may include, in part, a standard push button electric switch, and a standard key lock.

These objects are attained by a construction and arrangement which may be stated in general terms as including a base housing in which a standard push button electric switch is mounted, and a cover housing, adapted to provide a gasket sealed closure for the base housing and in which cover housing a standard key lock is mounted, the bolt of the key lock being adapted for selective engagement with a reciprocating switch operating plunger which is mounted in the cover housing and has an external end adapted to be pushed when the key lock is unlocked for abutting the lower end of the plunger against the outer end of the encased push button whereby the button may be operated for closing an electrical circuit such as a circuit necessary to operate the aforesaid garage opening and closing device.

A preferred embodiment of the invention is illustrated in the accompanying drawing, forming part hereof, in which:—

Figure 1 is a front elevation view of the improved key locking electric switch;

Fig. 2, a vertical axial sectional view thereof as on line 2—2, Fig. 1; and

Fig. 3, a fragmentary sectional view thereof as on line 3—3, Fig. 2.

Similar numerals refer to similar parts throughout the several views.

The improved key locking electric switch indicated generally at 1 preferably includes a base housing 2 which may be and preferably is a standard base housing, and, mounted in its interior, a standard push button electric switch indicated generally at 3 and including a spring pressed push button 4 normally maintaining an open circuit in an electrical circuit of which the wires 5 and 6 connected to the switch terminals 5' and 6' may be the lead wires, and which wires may extend into the base housing 2 as through the conduit 7 screwed into a suitable aperture 8 formed in a usual way in one end of the base housing.

When the push button 4 is inwardly pressed, against the outward pressure of its spring, the electric switch 3 is operated in a usual manner to close the circuit of which the ends of the wires 5 and 6 may be the terminals.

The standard base housing 2 is usually provided with a flat cover plate, which has an aperture through which the push button 4 extends. For the present purposes, however the standard flat cover plate is removed, and an improved cover housing 9 forms a closure over the open end 10 of the base housing 2, and may be secured thereto as by means of screws 11 passing through suitable apertures in an outwardly extending flange 12 of the cover housing and into suitable threaded apertures in an inwardly extending flange 13 of the base housing, and there being preferably provided between the adjacent flanges 12 and 13, a gasket 14 whereby an effective water tight joint closure is formed between the base housing and the cover housing.

The cover housing preferably includes side walls 15 extending outwardly from the flange 12, and merging with a front wall 16 which may be parallel with, but outwardly spaced a substantial distance away from the front edges of the opening 10 of the base housing.

The front wall 16 of the cover housing is provided with a suitable bearing aperture 17 in which a reciprocating plunger 18 is slidably mounted, and extends outwardly from the front wall 16 terminating preferably in the enlarged outer push head 19,

and the inner end 20 of the plunger extends into the interior of the cover housing for abutment against the outer end of the push button 4, whereby the plunger 18 may be 5 pushed to inwardly press the push button 4 and operate the switch 3.

The plunger 18 is provided with an annular groove 21 intermediate its outer and inner ends, and adapted to selectively receive the outer notched end 22 of the bolt 23 of a key operated lock 24 of a usual design. The lock 24 is mounted in the interior of the cover housing and has a key barrel 25 extending outwardly through a 10 suitable aperture in the front wall 16 of the cover housing, whereby the key lock may be exteriorly operated by a suitable key 26 for extending and retracting its bolt.

The normal position of the push button 20 4 is as illustrated in Fig. 2, and in order to operate the switch 3 for closing the circuit in which it is connected, the outer end of the push button must be pushed inwardly until it is substantially flush with the outer 25 face 27 of the switch 3.

The groove 21 is normally opposite the notched bolt end 22, and when the bolt is extended in normal locked position, the plunger 18 is prevented from being pushed 30 inwardly beyond the clearance limits of the groove, which limits are less than the distance it is necessary to push the plunger 18 in order to have its end 20 push the push button 4 the distance necessary to operate 35 the switch.

When the bolt 23 is retracted by operation of the key 26, the plunger 18 is free to be pushed inwardly the distance necessary to permit operation of the switch.

40 The lock 24 is preferably of the type including a spring normally pressing the bolt 23 outwardly for normal engagement with the groove 21 excepting when the bolt is retracted against the pressure of the spring, 45 by the key 26.

Accordingly the improved key locking switch may be located in any desired exterior position adjacent a garage door or the like, an automobile may be driven opposite the switch, and the driver of the automobile may use his key to retract the bolt 23, whereby he may push the plunger 18 inwardly and thereby push the push button 4 inwardly to operate the switch.

50 The device is not only adapted for such uses, but may also be used for outside light switches and the like, where a continuous pressure may be desired upon the push button 4.

55 For this purpose an annular groove 30

may be provided in the plunger 18 and adapted to receive the grooved end of the lock bolt 23, to hold the switch in closed position.

I claim:

1. A key locking electric switch including a base housing, a push button operated electric switch mounted in the base housing, a cover housing for the base housing, a reciprocating plunger mounted in the 70 cover housing and having its outer end extending exteriorly thereof and its inner end extending in the housing for abutment against the outer end of the push button, means urging the push button toward the 75 plunger, a key lock in the housing having a bolt for selective stop engagement with the plunger, the lock being adapted for operation by an exteriorly inserted key for extending and retracting the lock bolt into 80 and out of stop engagement with the plunger.

2. A key locking electric switch including a base housing, a push button operated electric switch mounted in the base housing, a cover housing for the base housing, a reciprocating plunger mounted in the cover 85 housing and having its outer end extending exteriorly thereof and its inner end extending in the housing for abutment against the outer end of the push button, means urging the push button toward the plunger, an annular groove intermediate the ends of the plunger, a key lock in the housing having a bolt for selective stop engagement with the annular groove of the plunger, the lock 90 being adapted for operation by an exteriorly inserted key for extending and retracting the lock bolt into and out of the groove of the plunger.

3. A key locking electric switch including a base housing, a push button operated electric switch mounted in the base housing, a cover housing for the base housing, a reciprocating plunger mounted in the 100 cover housing and having its outer end extending exteriorly thereof and its inner end extending in the housing for abutment against the outer end of the push button, means urging the push button toward the plunger, an annular groove intermediate the ends of the plunger, a key lock in the housing having a notched bolt for selective stop engagement with the annular groove of the plunger, the lock being adapted for operation by an exteriorly inserted key for extending and retracting the lock notched bolt 105 into and out of the groove of the plunger.

In testimony that I claim the above, I have hereunto subscribed my name.

MORGAN J. LEWIS.
